Des. 229,828

Patented Jan. 8, 1974

229,828

PORTABLE CHEMICAL TOILET

William J. Hinkley, 106 E. Washburn,
La Crosse, Wis. 54601

Filed June 12, 1972, Ser. No. 261,741

Term of patent 14 years

Int. Cl. D25—99

U.S. Cl. D13—1 L

FIG. 1 is a view in perspective as seen from the top front and one side of a portable chemical toilet showing my new design.

FIG. 2 is a view in perspective as seen from the top and sides opposite those shown in FIG. 1.

FIG. 3 is a view in side elevation thereof; and

FIG. 4 is a view in front elevation thereof.

The bottom, not shown, is devoid of ornamentation.

I claim:

The ornamental design for a portable chemical toilet, as shown and described.
